Primary Examiner — April Rivas(74) *Attorney, Agent, or Firm* — Troutman Pepper
 Hamilton Sanders LLP(57) **CLAIM**

The ornamental design for a heat exchanger fin, as shown and described.

DESCRIPTION

FIG. 1 is a perspective view of our new design for a heat exchanger fin installed with an array of heat exchanger fins in a heat exchanger for a tankless water heater;

FIG. 2 is a top front perspective view of our new design for a heat exchanger fin;

FIG. 3 is a bottom back perspective view thereof;

FIG. 4 is a left elevation view thereof;

FIG. 5 is a right elevation view thereof;

FIG. 6 is a front elevation view thereof;

FIG. 7 is a back elevation view thereof;

FIG. 8 is a top plan view thereof; and,

FIG. 9 is a bottom view thereof.

The broken lines shown in the figures illustrate the environment in which the heat exchange fin is installed and form no part of the claimed design.
